UNITED STATES PATENT OFFICE.

CARL J. SCHUSTER, OF MILWAUKEE, WISCONSIN, ASSIGNOR OF ONE-FOURTH TO ANTHONY W. H. HARTMAN AND ONE-FOURTH TO LOUIS E. H. WILL, BOTH OF MILWAUKEE, WISCONSIN.

BOTTLE-CLOSURE.

1,369,843.

Specification of Letters Patent. Patented Mar. 1, 1921.

Application filed September 23, 1919. Serial No. 325,737.

To all whom it may concern:

Be it known that I, CARL J. SCHUSTER, a citizen of the United States, residing at Milwaukee, in the county of Milwaukee, State 5 of Wisconsin, have invented a new and useful Bottle-Closure; and I do hereby declare the following to be a full, clear, and exact description of the invention, such as will enable others skilled in the art to which it 10 appertains to make and use the same.

This invention relates to an improvement in closures or caps for bottles and jars, and has particular reference to a device of this character which provides a tight seal for 15 relatively wide mouthed receptacles by a simple telescopic engagement of the cap onto the bottle or jar mouth.

Frequently the contents of a container become spoiled by reason of the failure of the 20 cover being properly placed thereon in an air-tight manner. This is especially true of containers provided with a screw threaded cover or cap which as a rule is not screwed down sufficiently when placed on the mouth 25 of a bottle to make the necessary seal, or when the threads of the cap jam and get stuck even at the very beginning of first turn while trying to screw cap on. Accordingly, the present invention has in view the 30 provision of a novel sealing cap which may be securely fastened to the mouth of a bottle in a quick and expeditious manner, and at the same time provide an effective seal.

A further object of the invention is to construct a cap which provides an augmented seal by reason of parts of the cap engaging both the interior and exterior of the mouth 35 of the bottle or vessel.

With these and other objects in view, the 40 invention consists in certain novel combinations and arrangements of the parts as will more fully appear as the description proceeds, the novel features thereof being pointed out in the appended claim.

For a full understanding of the invention, 45 reference is to be had to the following description and accompanying drawings, in which:—

Figure 1 is a perspective view of my improved cap showing the holding ribs thereof.

Fig. 2 is a vertical sectional view of my improved cap fitted to the mouth of a vessel having a relatively smooth cap receiving mouth portion.

Fig. 3 is a view similar to Fig. 2 showing 55 the mouth provided with an annular keeper groove for coöperating with the holding ribs of the cap.

Fig. 4 is a vertical sectional view of the cap carrying an interior sealing disk which 60 is adapted to engage with the inner surface of the bottle mouth to provide an augmented seal.

Fig. 5 is a fragmentary sectional view showing a modification which combines the 65 features of Figs. 3 and 4.

Corresponding and like parts are referred to in the following description and indicated in all the views of the drawings by the same reference characters.

In carrying the present invention into effect it is proposed to employ a cap 1 which may be made of metal or fiber and essentially comprises a body portion 2 and a depending annular flange portion 3 for telescopically engaging over the mouth 4 of a bottle, jar, or the like. The interior of the body 2 of the cap may be provided with a suitable liner 5 if desired, to prevent the contents of the vessel becoming directly in 80 contact with the cap, and also constitute a seal.

One of the novel and distinctive features of the invention resides in the provision of clutching means in the depending flange 85 portion 3 of the cap. Thus it will be observed from the drawings that it is proposed to provide the said flange with a plurality of inwardly projecting ribs 6 adapted to engage directly with the exterior of the 90 bottle or jar mouth, and which by reason of the inherent resiliency of the flange and the constricted diameter thereof produced by the inwardly projecting ribs will exert a superior gripping or clutching effect on the 95 mouth of the bottle to tightly position the cap in place but at the same time permit its ready removal by a simple combined rotary and longitudinal movement. As will be observed from the drawings the ribs 6 100 are vertically arranged in the flange 3 and may be spaced at any desired or required distance to obtain the desired holding effect, and terminate short of the top and bottom of the flange.

As shown in Fig. 3 of the drawings, the vertical holding ribs 6 may coöperate with a suitable annular groove 7 or its equiva-

lent formed in the peripheral surface of the bottle mouth 4. When the cap 1 is telescopically applied to a bottle mouth provided with the groove 7 the ribs 6 will snap into the same and thus effectively prevent accidental displacement of the cap from the bottle mouth, but at the same time will permit of its facile removal by the slightly circular and upwardly lifting movement here-
5 tofore referred to. That is to say, that although the ribs 6 may be seated in the groove 7 the same may be readily removed therefrom by a slight twisting motion which will cause the ribs to ride out of the groove and
10 permit the free removal of the cap by a straight longitudinal pull.

A further novel and distinctive feature of the invention is found in the embodiment thereof shown in Fig. 4 of the drawings, 20 wherein the cap 1 heretofore described has the annular bead portion 8 which provides an annular recess for receiving and holding in place a novel sealing cap 9 such for instance as that shown in my former Patent
25 No. 1,162,519, dated November 30, 1915, and which is provided with a depending retaining flange 10 adapted to engage with the interior of the bottle mouth. This form of the invention provides an augmented and
30 air-tight seal, and the metallic cap acts as a carrier for the sealing disk 9. By reason of the novel manner of assembly the interior sealing disk and cap may be conveniently fitted to the bottle or jar mouth by a
35 simple telescopic movement, and the combined effect of this arrangement is to provide a positive interior air-tight seal and an exterior clutching means for securely holding the entire cap assembly in place.

40 Fig. 5 illustrates a slight modification in which the sealing disk 9 is used in combination with the cap structure shown by

Fig. 3, the crimped disk 9 of Fig. 4 being substituted for the plain sealing disk 5 of Fig. 3. The annular bead portion 8 not 45 only provides a recess to receive the sealing disk, but also provides a finger piece which enables the closure to be conveniently grasped when placing it in position or removing it therefrom. 50

Without further description it is thought that the features and advantages of the present invention will be readily apparent, and it will of course be understood that changes in the form, proportion and minor 55 details of construction may be resorted to without departing from the spirit of the invention or scope of the appended claim.

Having thus described the invention, what I claim as new and desire to secure by Letters Patent, is:—

A sealing cap comprising a sheet metal body formed with a depending resilient clutching flange adapted to slip upon the neck of a container with a telescoping action, an annular crimped portion being provided at the base of the clutching flange which forms an exterior finger piece and an interior pocket, and an interior sealing disk arranged within the body and having edge 70 portions thereof received within an interior pocket to hold the sealing disk in position, said sealing disk being formed with a depending annular flange which is adapted to enter the neck of the container and expand peripherally into a close engagement therewith. 75

In testimony whereof I have signed my name to this specification in the presence of two subscribing witnesses.

CARL J. SCHUSTER.
